United States Patent Office

Des. 196,575
Patented Oct. 15, 1963

196,575

CHAIR OR THE LIKE

Herbert Ritts, P.O. Box 64336, Los Angeles, Calif.

Filed Jan. 21, 1963, Ser. No. 73,244

Term of patent 7 years

(Cl. D15—1)

I claim:

The ornamental design for a chair or the like, substantially as shown.
